UNITED STATES PATENT OFFICE.

CHARLES EUGENE SIDES, OF LEXINGTON, NORTH CAROLINA.

GASOLINE DISPENSER.

Application filed July 20, 1921. Serial No. 486,155.

To all whom it may concern:

Be it known that I, CHARLES E. SIDES, a citizen of the United States, residing at Lexington, in the county of Davidson and State 5 of North Carolina, have invented a new and useful Gasoline Dispenser, of which the following is a specification.

This invention relates to dispensing tanks, especially designed for dispensing gasoline 10 or the like, the primary object of the invention being to provide a tank of the visible type, wherein the consumer may observe the quantity of fluid passing from the tank.

Another object of the invention is to provide a device of this character which may 15 be attached or applied to dispensing tanks which are now in common use, it being unnecessary to make elaborate alterations in the construction of the tank to apply the 20 invention.

With the foregoing and other objects in view which will appear as the description proceeds, the invention resides in the combination and arrangement of parts and in the 25 details of construction hereinafter described and claimed, it being understood that changes in the precise embodiment of the invention herein disclosed, may be made within the scope of what is claimed, without 30 departing from the spirit of the invention.

Referring to the drawings:—

Figure 1 is a side elevational view of a device constructed in accordance with the present invention, showing the same as applied to a tank.

Figure 2 is a plan view of the supporting bracket employed in connection with the supporting pipe, taken on line 2—2 of Figure 1.

Figure 3 is a sectional view taken on line 3—3 of Figure 1.

Figure 4 is a vertical sectional view through the visible tank.

Referring to the drawings in detail, the 45 reference character 5 designates the body portion of the tank, the same being of the usual construction and having an upwardly extending discharge pipe 6 which communicate with the interior of the body portion in 50 the well known manner.

A feed pipe 7 has communication with the pipe 6 and is connected thereto through the medium of the pipe 8 and couplings 9 and 10 respectively, the pipes being shown as 55 relatively long and provided with a coupling 11 at the lower end thereof, which cou-

pling supports the pipe 12 which extends therethrough.

The inner end of the pipe 21 supports a coupling 13, in which the pipe 14 is positioned, the lower end of the pipe 14 being capped by means of the cap 15. This pipe 14 embodies a supporting pipe and is connected to the pipe 6 by means of the supporting bracket indicated generally by the 60 reference character 16, which bracket includes the spaced threaded rods 17 on which operate pairs of movable bars 18 and 19 respectively, the bars of each pair having cooperating cut out portions to grip the 65 pipes to which the same are secured.

Suitable nuts indicated at 20 operate on the threaded rods 17 which nuts may be moved against the bars 18 to cause the same to closely grip the pipes associated therewith. The pipes 7 form a support for the 75 visible receiving tank 21, which is formed preferably of glass but it is to be understood that a metal tank having a transparent front wall may be employed if so desired. 80

This tank 21 is supported within a metal housing 22 which embodies an upper disk-like wall 23 and a lower wall 24, the latter wall being of a construction identical with the wall 23, the walls 23 and 24 being held in 85 spaced relation by means of the circular metal housing 25, which is provided with a vertical cut away portion to accommodate the removable transparent member 26 which is held within the housing in any suitable 90 manner.

Connecting rods 27 have their ends extended through suitable openings provided in the walls 23 and 24, nuts 28 being positioned on the ends thereof to clamp the walls 95 23 and 24 into close engagement with the upper and lower edges of the housing 25. In order that the transparent receiving tank 21 may be held against movement longitudinally of the pipe 7, nuts 29 are provided, which nuts engage the walls 23 and 24 of the housing 25. A spacing block 30 is positioned between the upper end of the transparent receiving receptacle 21 and the inner surface of the wall 23 of the housing, whereby the tank 21 is held in proper spaced relation with its housing. 100

Formed in the pipe 7 are the openings 31, 32 and 33 respectively, the openings being for the purpose of providing communication 105 between the pipe 7 and the interior of the visible tank 21, so that as fluid passes

through the pipe 7 the tank will become filled.

A vent pipe 34 provides communication between the atmosphere and tank 21, there being provided a suitable valve at the upper end of the vent pipe for permitting air to exhaust therefrom as the tank is being filled. Supported on one of the spacing rods 27 is a movable bar 35 carrying the extensions 36 which indicate quantities of fluid in the tank. This bar 35 is provided with lateral lugs which are apertured to accommodate the rods to which the same is applied, set screws 37 being provided for securing the bar in predetermined positions of adjustment to insure an accurate reading of the quantity of fluid in the tank 21.

Communicating with the tank through the coupling 11 is a discharge pipe 38 which is in the form of a flexible tubing, which may carry a suitable discharge nozzle not shown, on the free end thereof, which nozzle may be inserted in the usual filling opening of a gasoline tank to direct fluid thereto.

25 A valve member 39 is positioned between the coupling 11 and flexible tube 38 to control the passage of fluid from the tank.

It might be further stated that the bar 35 which carries the lateral extensions 36 contacts with the transparent member 26 to support the same in position.

In the use of the device, the usual pump mechanism is employed for forcing the fluid

into the transparent tank 21, whereupon the consumer may observe the quantity of fluid 35 sold him. When the desired quantity has been forced into the tank 21, the valve member 39 is operated to provide communication between the tank and the tubular member 38, whereupon the fluid may pass from the 40 tank.

Having thus described the invention, what is claimed as new is:—

In combination with a dispensing tank and the discharge pipe thereof, a receiving tank 45 formed of transparent material associated with the dispensing tank and adapted to receive fluid therefrom, a circular metallic casing housing the receiving tank, said casing having an opening, a transparent member 50 disposed in the opening, a wall at each end of the circular housing, a rod connecting the walls, an adjustable bar supported by the rod, said bar carrying lateral extensions, a discharge pipe in communication with the receiving tank, and a valve for controlling the passage of fluid from the receiving tank 55 to the discharge pipe.

In testimony that I claim the foregoing as my own, I have hereto affixed my signature 60 in the presence of two witnesses.

CHARLES EUGENE SIDES.
